UNITED STATES PATENT OFFICE.

WILLIAM DEWEY STAIR, OF MOUNT UNION, PENNSYLVANIA.

SEAT PAD FOR SPORTSMEN'S COATS.

Application filed July 28, 1926. Serial No. 125,482.

This invention relates generally to sportsmen's coats of the fishing and hunting type, but has more particular reference to a seat pad associated therewith.

5 The primary object of the invention is to provide a seat pad for sportsmen's coats whereby a cushion will be provided for the sportman while sitting in a boat, duck blind, et cetera.

10 The invention further aims to provide a seat pad that is attached directly to the coat, and this in such a manner that the same will depend therefrom and seek a position upon a seat when the sportsman moves to sitting position.

15 A further object of the invention resides in the provision of a combination coat and seat pad wherein the pad may be supported entirely within the coat when the use of the same is not required.

20 Other objects will become apparent as the nature of the invention is better understood, the same comprising the novel form, combination, and arrangement of parts hereinafter 25 more fully described, shown in the accompanying drawing and claimed.

In the drawing wherein like reference characters indicate corresponding parts in both the views:

30 Figure 1 is an inner side elevation of a sportsman's coat equipped with my seat pad, and

Figure 2 is a detail transverse section of the pad per se.

35 In carrying out the present invention, the sportsman's coat 5 is provided at its inner side and at the back thereof with a pair of spaced vertically extending elongated tabs 6-6, the lower ends of which are secured to the lower edge of the coat by stitching or the like while the opposite ends of the pads are provided with button holes for receiving buttons 7-7 upon the inner side of the coat 5 in vertical alignment with the secured ends 40 of the tabs.

45 The pad per se is designated by the reference character 8 and is preferably of the rectangular configuration as disclosed, the same consisting of a fabric or leather jacket 9 within which is a filler of felt or other suitable padding material designated 10. The upper edge of the pad is equipped adjacent opposite ends with a pair of metallic rings 50 11-11 through which the tabs 6-6 are to be engaged prior to the securing of the same

at their free ends to the inner side of the post by reason of the button and hole on the coat and in the tabs respectively.

It will thus be seen that the pad will always depend from the lower edge of the coat 60 so that the same will engage upon the seat when the sportsman moves to sitting position so that he may have free use of his hands while fishing, hunting, or the like.

65 In order that the pad may be arranged entirely within the coat when the same is not necessary for use, the upper edge of the pad between the rings 11-11 is equipped with a fabric tongue 12 within which is a button hole for receiving a button 13 upon the inner 70 side of the coat 5 intermediate the before-mentioned buttons 7-7. Obviously the pad may be slid upwardly entirely in back of the coat and secured in this position by arranging the button 13 within the button hole of 75 the tongue 12.

80 It will thus be seen that I have provided a highly novel, simple, and efficient form of seat pad for sportsman's coats that is well adapted for all the purposes heretofore designated.

Having thus described the invention, what I claim as new and desire to secure by Letters Patent is:

85 1. In combination with a coat of the character described, a seat pad normally depending below the coat, a sliding connection between the pad and the back side of the coat at the interior thereof, and means whereby the seat pad may be supported in position 90 entirely within the coat when not in use.

95 2. In combination with a coat of the character described, a pair of elongated tabs secured at their lower ends to the lower edge of the coat at the inner side thereof, means whereby the opposite ends of the tabs may be detachably secured to the inner side of the coat, and a seat pad supported in depending relation with respect to the coat by reason of said tabs, said pad having 100 means through which the tabs may be passed.

105 3. In combination with a coat of the character described, a pair of elongated tabs secured at their lower ends to the lower edge of the coat at the inner side thereof, means whereby the opposite ends of the tabs may be detachably secured to the inner side of the coat, a seat pad supported in depending relation with respect to the coat by reason of 110

- said tabs, said pad having means through which the tabs may be passed, and means whereby the pad may be supported entirely within the coat when the same is not in use.
- 5 4. In combination with a coat of the class described, a seat pad pivotally and slidably connected to the lower portion of the back of the coat, said pad adapted to depend below the lower edge of the coat when in one position, the pad being adapted to be entirely concealed within the coat when in another position.
- 10 5. In combination with a coat of the class described, a seat pad pivotally and slidably connected to the lower portion of the back of the coat, said pad adapted to depend below the lower edge of the coat when in one position, the pad being adapted to be entirely concealed within the coat when in
- another position, and means for securing the pad in the last mentioned position.
6. In combination with a coat of the class described, a seat pad pivotally and slidably connected to the lower portion of the back of the coat, said pad adapted to depend below the lower edge of the coat when in one position, the pad being adapted to be entirely concealed within the coat when in another position, means for securing the pad in the last mentioned position, said means comprising a tongue having a button hole formed therein carried by the upper edge portion of the pad, and a button for co-operation with said button hole secured to the inner side of the back portion of the coat.
- 25 30 35

In testimony whereof I affix my signature.

WILLIAM DEWEY STAIR.
